CIRCUIT BREAKER

Herbert J. Webb, Forest Hills, Benjamin P. Baker, Turtle Creek, and Arthur M. Wahl, Wilkinsburg, Pa., assignors to Westinghouse Electric & Manufacturing Company, East Pittsburgh, Pa., a corporation of Pennsylvania

Application July 29, 1943, Serial No. 496,576

11 Claims. (Cl. 200—48)

The invention relates to high-voltage circuit breakers and, more particularly, to high-voltage circuit breakers of the compressed gas type in which at least some of the parts are supported by porcelain insulators.

The pole units of high-voltage circuit breakers of the compressed gas type are usually rigidly supported by one or more rigidly-mounted hollow porcelain insulators, and the moving contact or contacts are operated at high-speed by compressed gas-motor means which in some cases is mounted in a housing supported on the insulator means. Upon operation of the circuit breaker, very high impact forces, and vibrations or oscillations are produced which set up high stresses in the rigidly-mounted insulators, despite the provision of shock absorbers in the motor means. The impact forces and oscillations resulting from impact of the contact means and moving parts may be augmented by those resulting from rebound of the moving parts and also by the transient vibrations set up by the sudden initial application of compressed gas for operating the breaker. If the circuit breaker embodies a vertically movable interrupting contact and driving piston therefor, and a disconnecting contact member and driving piston therefor disposed at an angle to the vertical axis, the impact forces and oscillations will be both vertical and horizontal and corresponding stresses will be set up in the supporting insulators. The high stresses set up in the insulators have in a number of cases resulted in breakage of the insulators.

The provision of ordinary resilient washers between the ends of the insulators and the parts to which the insulators are bolted does not solve the problem of preventing excessive stressing of the insulators as such an arrangement only allows freedom of movement of the insulator in one direction to take up the shocks and oscillations, namely in the direction which compresses the washer. In such an arrangement, the bolts do not allow movement in the opposite direction nor tilting or pivoting movement for the horizontal components of impact and oscillation.

An object of the invention is the provision of a circuit breaker of the type having parts supported by one or more porcelain insulators with a novel resilient mounting arrangement for the insulators to materially reduce the stresses in the insulators resulting from impact forces and oscillations produced upon operation of the breaker.

Another object of the invention is the provision of a circuit breaker having parts supported

by porcelain insulators with flexible or resilient supports for either one or both ends of the insulators to absorb the impact forces and oscillations resulting from operation of the breaker without overstressing the insulators.

Another object of the invention is the provision of a circuit breaker comprising a supporting insulator with a resilient shock-absorbing connection between the insulator and the part supported thereby or between the insulator and the part on which it is supported or between the insulator and both parts, to provide flexibility and absorb the impact forces and oscillation forces resulting from operation of the breaker without overstressing the insulator.

Another object of the invention is the provision of a circuit breaker of the type having one or more porcelain supporting insulators with means for resiliently supporting or securing the insulators to permit both horizontal and vertical oscillations of the structure to prevent excessive stresses in the insulators.

Another object of the invention is the provision of a circuit breaker of the compressed gas type having a vertically movable interrupting contact and a movable disconnecting contact disposed for movement at an angle to the vertical axis, both supported by porcelain insulators, with resilient supports for the insulators to provide for vertical and horizontal oscillations of the structure and absorption of the impact and oscillation forces without overstressing the insulators.

The novel features that are considered characteristic of the invention are set forth in particular in the appended claims. The invention itself both as to structure and operation, together with additional objects and advantages thereof will be best understood from the following detailed description of several embodiments thereof when read in conjunction with the accompanying drawings, in which:

Figure 1 is a side elevational view partly in section, showing a compressed gas circuit breaker to which the invention is applied;

Fig. 2 is an enlarged fragmentary sectional view illustrating the resilient mounting of one of the porcelain insulators on the base or frame;

Fig. 3 is an enlarged fragmentary sectional view showing a modification of the resilient mounting of the supporting insulator;

Fig. 4 is an enlarged fragmentary view, partly in section, showing the operating mechanism casting of a circuit breaker with the insulators resiliently secured thereto in accordance with a further modification of the invention, and

Fig. 5 is a sectional view taken on the line V—V of Fig. 4 showing the manner of attachment of the casting and lower insulators to the resilient mounting plate between the casting and the supporting insulators.

The features of the present invention are illustrated as applied to a compressed gas circuit breaker similar to that disclosed in the copending application of L. R. Ludwig, et al., Serial No. 431,394, filed February 18, 1942, and assigned to the assignee of the present application. Only as much of the circuit breaker structure is shown in the drawings of this application and described herein as is deemed necessary for a complete understanding of the present invention. For other details of the circuit breaker, reference may be had to the aforementioned copending application Serial No. 431,394. While the present invention is illustrated as applied to a particular circuit breaker, it is to be understood that the invention is also applicable to other circuit breaker structures embodying porcelain supporting insulators.

Referring to Fig. 1 of the drawings, the reference numeral 11 designates a base or frame fabricated of structural steel or other suitable material. Rising from the left-hand end of the base 11 are a plurality of columns of tubular supporting insulators 13 and 15 of vitreous insulating material such as porcelain. A third supporting insulator column, not visible in the drawings, but similar to the column 15, is disposed in back of the column 15. Each of the insulator columns 13 and 15 in the embodiment shown consists of a stack of two standard porcelain insulators secured together, and the three supporting columns are connected together by a bracing plate 18. The size of the insulators, the number in each column, and the number of supporting columns will of course depend upon the voltage and strength requirements.

Supported on the upper end of the plurality of the supporting insulators is an operating mechanism housing or casting 19 on which is supported a hollow porcelain supporting insulator 21 which, in turn, supports a circuit interrupting element 23. A hollow porcelain insulator 25 extends upwardly from the element 23 and has a metallic terminal cap 27 secured on its upper end.

Each of the insulators 13, 15, 21 and 25 is of conventional construction having flanged metallic end fittings 20 rigidly secured to each end thereof for securing the insulator.

A stationary contact 29 extends downwardly from the cap 27 into the chamber of the circuit interrupting element 23. A movable contact member 31 cooperates with the stationary contact 29 and extends downwardly through the element 23 and hollow insulator 21. The lower end of the movable contact member 31 extends into the housing 19 and is connected to an actuating piston 33 movable in a cylinder 35 mounted in the housing 19. The piston 33 is adapted to be operated by compressed gas to actuate the movable contact 31 to open and to closed circuit position.

The contacts 29—31 form the current interrupting or arcing contacts of the breaker and are electrically connected in series with a pair of disconnect contacts which are arranged to be opened after the arcing contacts during a circuit opening operation of the breaker and closed after the arcing contacts have closed during a closing operation of the breaker. The disconnect con-

tacts comprise a relatively stationary disconnect contact 37 mounted on a terminal cap 39 secured to the upper end of a hollow porcelain insulator 41 on the right-hand end of the base, and a co-operating movable disconnect contact member 43 in the form of a rod which is mounted in bearing means on the housing 19 for straight-line movement into and out of engagement with the stationary disconnect contact 37. The axis of movement of the disconnect contact member 43 and its actuating piston is at an angle to the axis of movement of the movable arcing contact 31. The inner end of the movable disconnect contact member 43 is connected to an operating piston 45 which moves in a cylinder 47 mounted in the housing 19. The piston 45 is adapted to be operated by compressed gas to actuate the disconnect contact member to open and to closed circuit position.

The movable arcing contact member 31 and the movable disconnect contact member 43 are electrically connected in series by electrical connections including finger contacts slideably engaged by the contact members 31 and 43. The hollow insulator 41 serves as a housing for transformers and other suitable electrical instrumentalities necessary for the control of the circuit breaker. External circuit connections to the circuit breaker are made to terminals 49 and 51 on the terminal caps 27 and 39. When the circuit breaker is in closed position, current flows through the breaker from the terminal cap 27 through the stationary contact 29, movable arcing contact 31, through electrical connections to the movable disconnect contact member 43, to the stationary contact 37 and terminal cap 39.

Extinction of the arc drawn by the movable arcing contact member 31 upon interruption of the circuit is accomplished by a blast of compressed gas or air directed to the chamber of the interrupting element 23.

Fluid under pressure, in this instance compressed air, for extinguishing the arc and also for operating the movable contacts 31 and 43 is stored in a tank 53 mounted within the frame or base 11. Extending from the left-hand end of the air-storage tank 53 is a pipe 55 which has mounted thereon and in communication therewith a blast valve 51. The blast valve when opened admits a blast of compressed air from the tank 53 through the passage of the supporting insulator column 13 and through a pipe 59 and the passage of insulator 21 to the interrupting element 23 where it serves to quickly extinguish the arc drawn by the opening of the arcing contacts.

Closing operation of the circuit breaker is controlled by a closing control valve 61 connected to the pipe 55. When the valve 61 is operated to open position upon energization of its control electromagnet, compressed air is admitted from the tank 53 and supply pipe 55 through a pipe 63 and the passage through the insulator column 15 and a pipe 65 into the lower end of the cylinder 35. The piston 33 is driven upwardly by the compressed air thereby actuating the arcing contact 31 to closed position. As the piston 33 moves upwardly it uncovers a port in the side of the cylinder 35 whereupon compressed air is admitted through a pipe 67 into the lower end of the disconnect cylinder 47, causing the piston 45 to move the movable disconnect contact member 43 to closed circuit position completing the circuit through the breaker.

Opening operation of the circuit breaker is controlled by an opening control valve not visible in the drawings but disposed in back of the valve 61 and connected to the common supply pipe 55. When the opening control valve is opened upon energization of its control electromagnet, compressed air is admitted from the supply pipe 55 through the valve and through a pipe (not shown) and the passage of the other supporting insulator column behind the column 15 and through a pipe 71 into the upper end of the arcing contact operating cylinder 35. The compressed air drives the piston 33 downwardly to the bottom of the cylinder and thereby actuating the movable arcing contact 31 to open circuit position. As the piston 33 moves downwardly, it uncovers a port in the side of the cylinder 35 whereupon compressed air is admitted from the cylinder 35 through a pipe connection 73 into the upper end of the disconnect cylinder 47 causing the disconnect piston 45 to be moved to the lower end of the cylinder 47, thereby actuating the disconnect contact member 43 to the open-circuit position shown.

The control electro magnet for the blast valve 57 and the control electromagnet for the circuit breaker opening valve are arranged to be energized simultaneously to initiate opening operation of the circuit breaker so that a blast of compressed air will be directed to the arcing contacts simultaneously with the opening movement thereof.

Shock absorbing means (not shown) are provided for each of the operating pistons 33 and 45 as disclosed in the aforementioned copending application Serial No. 431,394, although other forms of shock absorbing means for the operating pistons may be used.

The control circuits for controlling the electromagnets which control the blast valve 57 and the opening and closing valves may be substantially the same as disclosed in the aforementioned copending application Serial No. 431,394.

The moving contacts 31 and 43 and the operating pistons 33 and 45 are operated at very high speeds, and although some of the kinetic energy of the moving parts is absorbed by the mechanism housing and the shock-absorbing means for the operating pistons, the entire pole unit mechanism above the insulators 13 and 15 is forced into oscillation. The oscillations produced by the operation of the arcing contact 31 and its operating piston 35 are in a vertical direction whereas the oscillations produced by the operation of the disconnect contact 43 and its piston 45 have both a vertical and a horizontal component. These impact and oscillation forces may be augmented by the transient vibration produced by the sudden application of compressed air to the operating pistons. If the supporting insulators are rigidly supported and secured in the usual manner, the impact forces and oscillations resulting from the operation of the circuit breaker are very apt to break the insulators, and in fact breakage of the insulators has occurred in a number of cases from this cause.

In accordance with the present invention, means are provided for resiliently mounting or securing the supporting insulators at one or both ends to permit both vertical and horizontal oscillations of structure to absorb the impact and oscillation forces and prevent excessive stressing of the insulators.

Referring to Figs. 1 and 2, the lower insu-

lators units 13 and 15 of each of the plurality of supporting columns are mounted on the top plate of the base 11 by means of a plurality of bolts or cap screws 77 which extend through holes 79 provided therefor in the flange of the metal end fitting 20 of the insulator and thread into the top plate of the base 11. The bolt holes 79 in the insulator flange are of larger diameter than that of the bolts or screws 77 so as to permit up and down movement and rocking movement of the insulator relative to the top plate of the base 11 and the bolts 77. A washer 81 of resilient material such as rubber, neoprene, thiocol, cork or other suitable resilient material is disposed between the metal end fitting 20 of the insulator and the top plate of the base 11. An annular gasket 83 of resilient material seated in an annular recess in the top plate of the base 11 and disposed between the washer 81 and the top plate of the base may also be provided. This gasket 83 assists the washer 81 in making the joint between the insulator fitting 20 and the top plate of base 11 gas-tight to prevent leakage of compressed air through this joint. Encircling each of the bolts 77 and disposed between the head of the bolt and the flange of the insulator fitting 20 is a resilient spring means consisting of a plurality of convex shaped spring washers 85 arranged in alternating fashion one washer with its convex side up and the next adjacent washer having its convex side down.

A flat metal retaining ring 86 is disposed around the outside edge of the resilient washer 81 between the flange of the insulator fitting 20 and the top plate of the base. The bolts 77 pass thru openings in this retaining ring to hold it in position. The ring 86 serves to prevent the edge portion of the resilient washer 81 from bulging out in the spaces between the bolts 77.

In tightening the bolts 77, the metal end fitting of the insulator comes down securely on the resilient washer 81 and the spring washers 85 are compressed or deflected a predetermined amount. With this resilient mounting arrangement it is evident that for vertical oscillations of the supporting insulator and structure above it the insulator is floated between the resilient washer 81 and the spring washers 85, these resilient elements permitting up and down oscillations of the insulator relative to the base 11. For horizontal or rocking oscillations of the mechanism housing 19 and supporting insulators 13 and 15, the supporting insulators can rock or pivot relative to the base 11, compressing the resilient washers 81 on one side and compressing the spring washers 85 on the other side and vice versa as the structure rocks. The resilient washers 81 and spring washers 85 provide sufficient flexibility to absorb the shock forces and oscillation forces resulting from the operation of the breaker without overstressing the porcelain supporting insulators.

The upper metal end fittings of the upper porcelain supporting insulators 13 and 15 of each supporting column may also be, and preferably are, resiliently secured to the bottom wall of the mechanism housing 19 in the same way that the lower supporting insulators are resiliently mounted on the base 11 as described above and shown in Fig. 2. With the upper insulators 13 and 15 resiliently secured to the bottom wall of the mechanism housing 19, the mechanism housing 19 and structure carried thereby can oscillate up and down and also pivot or rock relative to the supporting insulators 13 and 15 so as to absorb

the shock and oscillation forces without overstressing the insulators.

The method of resiliently mounting or securing the supporting insulators not only provides sufficient flexibility to permit horizontal and vertical oscillations and absorb the shock forces and oscillation forces to prevent overstressing of the insulators, but it also eliminates the necessity of having the supporting porcelain insulators all exactly the same length and the mounting surfaces of their metal end fittings all in exactly the same plane. The parts can be easily assembled without danger of straining the insulators despite variations of manufacture. A good gas-tight joint is also obtained by the resilient mounting arrangement.

The hollow insulator 21, which supports the interrupting element 23 and the structure above it, may also be, and preferably is, resiliently mounted on the top wall of the mechanism housing 19 in the same way that the lower supporting insulators are resiliently mounted on the base 11 as has been previously described and shown in Fig. 2. This will enable the insulator 21 and the structure carried thereby to oscillate up and down and rock or pivot relative to the mechanism housing 19 thus providing sufficient flexibility to absorb the shock forces and oscillation forces without overstressing the insulator.

A modification of the resilient mounting or securing arrangement for the supporting insulators is shown in Fig. 3. Each of the lower supporting insulators of the plurality of supporting columns 13 and 15 of the circuit breaker may be resiliently mounted on the top of the base 11 in the manner shown in Fig. 3. In this figure of the drawings, 89 designates the top plate of the circuit breaker base 11. The lower end of each of the lower supporting insulators has a metal fitting 91 rigidly secured thereto. An annular relatively thin plate 93 of spring steel or other strong resilient metal is secured at its central portion to the bottom of metal fitting 91 by welding or other suitable securing means. The spring plate 93 is of slightly convex shape as shown in Fig. 3 so that its center portion is spaced above the base plate 89. Adjacent its outer peripheral edge the spring plate is secured to the base plate 89 by a plurality of cap screws or bolts 95, the bolts being arranged in spaced relation in a circle adjacent the outer edge of the spring plate 93. An opening 94 in the base plate 89 and the center opening 96 in the spring plate 93 are aligned with the passage through the insulator to permit the passage of compressed air through the insulator, and the outer edge portion of the spring plate is cemented to the base plate 89 to prevent leakage of moisture through the joint. The air conduit 98 which communicates with the passage through the insulator may be connected to a metal ring 97 secured to under side of the spring plate in the manner shown in Fig. 3. The upper end of the conduit 98 has a reduced portion which loosely slideably fits in the opening of the ring 97, and a resilient gasket 100 is disposed between the shoulder on the conduit 98 and the under side of the ring 97. The loose slideable connection between the conduit and the ring permits oscillating and tilting movement of the insulator relative to the conduit 98, and the gasket makes the joint gas-tight despite relative movement between the parts.

The resiliency of the spring plate 93 permits the supporting insulator to oscillate up and down and also to rock relative to the base plate 89, and

the shock forces and oscillation force resulting from operation of the breaker are thereby absorbed without excessively stressing the supporting insulator.

5 The upper end of each of the supporting insulator columns which support the operating mechanism housing 19 of the circuit breaker can also be resiliently secured to the bottom wall of the mechanism housing 19 by a spring plate 10 in the same manner as shown in Fig. 3. This will permit the mechanism housing 19 and the structure supported thereby to oscillate up and down to rock relative to the supporting insulators and the spring plates will thereby absorb the shock forces and oscillation forces without overstressing the insulators.

10 The insulator 21 of the circuit breaker may also be resiliently mounted on the upper wall of the mechanism housing 19 by a spring plate 20 mounting similar to that shown in Fig. 3 to provide flexibility for this insulator so that it will not be excessively stressed by the shock and oscillation forces resulting from operation of the circuit breaker.

25 Another modification of the invention is shown in Figs. 4 and 5. Referring to Fig. 4, the operating cylinder 35' for the movable arcing contact 31 and the operating cylinder 47' for the movable disconnect contact 43 are mounted on a metal casting 101 which corresponds to the mechanism housing 19 shown in Fig. 1. The arcing contact 31 is operated to open and closed position by a piston 33' in the cylinder 35', and the movable disconnecting contact 43 is operated to open and to closed position by a piston 45' in the same manner as previously described in connection with the Fig. 1 embodiment. The casting 101 is formed to provide a conduit 103 which communicates with the blast air passages of the insulators 13 and 21 for the flow of blast air to the interrupting element of the circuit breaker.

30 The base of the casting 101 is secured to a relatively thin spring steel metal plate 105 by a plurality of bolts 107 (Figs. 4 and 5) arranged in three circles, each of the circle of bolts being disposed concentric to the axis of a corresponding one of the columns of supporting insulators 13 and 15 as shown in Fig. 5. The flange of the upper metal end fitting 20 of the insulators of each supporting column 13 and 15 is secured to the resilient plate 105 by a plurality of bolts or cap screws 109 which extend through the resilient plate and thread into the flange of the insulator fitting 20. The bolts 109 for securing each insulator to the plate 105 are arranged in a circle which is of considerably larger diameter than the circle of the bolts 107 thus leaving a section of the plate 105 between the concentric circles of bolts 107 and 109 to provide flexibility between the mechanism casting 101 and each supporting insulator 13 or 15. The resiliency of this section of the plate 105 permits the mechanism casting 101 to oscillate up and down and also to rock a limited amount relative to the supporting insulators and thereby absorb the shock forces and oscillation forces resulting from operation of the circuit breaker without overstressing the supporting insulators. The lower end of the supporting insulators 13 and 15 of each column may be resiliently mounted on the base or frame 11 of the circuit breaker either in the manner shown in Fig. 2 or in the manner shown in Fig. 3.

35 The upper end of the mechanism casting 101 is provided with a relatively thin circular flange

III, and the flange of the lower end fitting 20 of the hollow insulator 21 is secured to the flange III by a plurality of cap screws 113. The casting is made of a suitable resilient metal, and the thin flange portion III thereof provides a resilient mounting for the upper insulator 21 to permit oscillation of the insulator 21 and structure carried thereby and absorb the shock forces and oscillation forces without overstressing the insulator.

The remaining structure of the circuit breaker is the same as that shown in Fig. 1 and described in connection therewith.

While several embodiments of the invention have been disclosed in accordance with the patent statutes, it is to be understood that various changes in the structure and arrangement of parts may be made without departing from some of the essential features of the invention.

We claim as our invention:

1. In a high-voltage electrical circuit breaker structure, circuit interrupting mechanism, tubular porcelain insulator means for supporting said circuit interrupting mechanism, and means resiliently securing said insulator means to a part of said circuit breaker structure for permitting vertical and horizontal oscillation of said insulator means relative to said part for preventing excessive stressing of said insulator means.

2. In an electrical circuit breaker, circuit interrupting mechanism, high-voltage insulator means supporting and bearing the weight of said circuit interrupting mechanism, and means resiliently mounting said circuit interrupting mechanism on said insulator means for permitting vertical oscillations and horizontal oscillations of said circuit interrupting mechanism relative to said insulator means in opposite directions from the normal position of said mechanism for preventing excessive stressing of said insulator means.

3. In an electrical circuit breaker, a base, tubular high-voltage insulator means of vitreous insulating material mounted on said base, circuit interrupting mechanism mounted on and supported by said insulator means, and means resiliently mounting said insulator means on said base for permitting vertical and horizontal oscillations of said insulator means relative to said base for preventing excessive stressing of said insulator means.

4. In an electrical circuit breaker, a base, tubular high-voltage insulator means of vitreous insulating material mounted on said base, circuit interrupting mechanism mounted on and supported by said insulator means, means resiliently mounting said insulator means on said base and means resiliently mounting said circuit interrupting mechanism on said insulator means for permitting vertical and horizontal oscillations of said mechanism relative to said insulator means and vertical and horizontal oscillations of said insulator means relative to said base for absorbing shock forces and preventing excessive stressing of said insulator means.

5. In a high-voltage electrical circuit breaker, a base, a plurality of high-voltage tubular supporting insulators of vitreous insulating material mounted on said base, circuit interrupting mechanism mounted on and supported by said insulators comprising a vertically movable current interrupting contact and actuating means therefor and a separate series connected movable disconnect contact member and actuating means therefor disposed for movement at an angle to

the vertical axis, means resiliently mounting said circuit interrupting mechanism on the upper ends of said insulators and means resiliently mounting said insulators on said base for permitting vertical and horizontal oscillations of said circuit interrupting mechanism relative to said insulators and vertical and horizontal oscillations of said insulators relative to said base for absorbing shock forces and preventing excessive stressing of said insulators.

6. In a high-voltage electrical circuit breaker, circuit interrupting mechanism, one or more tubular high-voltage insulators of vitreous insulating material supporting and bearing the weight of said circuit interrupting mechanism, means resiliently mounting said circuit interrupting mechanism on said one or more insulators for reducing shock forces and oscillation forces applied to said one or more insulators resulting from operation of the circuit breaker, said resilient mounting means comprising a washer of resilient material disposed between said mechanism structure and each supporting insulator, a plurality of bolts securing said insulator to said mechanism structure and resilient means on each bolt between the head of said bolt and said insulator.

7. In a high-voltage electrical circuit breaker, a base, one or more insulators mounted on said base, circuit interrupting mechanism mounted on and supported by said one or more insulators, and means resiliently mounting said one or more insulators on said base to prevent excessive stressing of said insulators, said resilient mounting means comprising a washer of resilient material disposed between each insulator and said base, a plurality of bolts securing said insulator on said base and spring means on each bolt between the head of said bolt and said insulator.

8. In an electrical circuit breaker, circuit interrupting mechanism, one or more tubular insulators of vitreous insulating material supporting and bearing the weight of said circuit interrupting mechanism, each insulator having a rigid fitting on each end thereof, means resiliently mounting said circuit interrupting mechanism on said one or more insulators to permit limited oscillation of said mechanism relative to said one or more insulators and to prevent overstressing of said one or more insulators comprising a relatively thin plate of resilient metal attached to the end fitting of each insulator and secured at a plurality of points adjacent to said circuit interrupting mechanism structure.

9. In an electrical circuit breaker, a base, one or more tubular insulators of vitreous insulating material mounted on said base, circuit interrupting mechanism mounted on and supported by said one or more insulators, each insulator having a rigid fitting secured to each end thereof, means resiliently mounting said one or more insulators on said base for permitting oscillation of said circuit interrupting mechanism and said one or more insulators relative to said base and for preventing excessive stresses in said one or more insulators comprising a relatively thin plate of resilient metal attached to the fitting of each insulator and secured at a plurality of points to said base.

10. In an electrical circuit breaker, a base, a plurality of insulators of vitreous insulating material mounted on said base, circuit interrupting mechanism mounted on and supported by said insulators, and means resiliently mounting said insulators on said base to permit oscillation of

said mechanism and insulators relative to said base and prevent excessive stresses in said insulators comprising a separate relatively thin mounting plate attached at its central portion to the end of each insulator and secured at a plurality of points adjacent its edge to said base.

11. In an electrical circuit breaker, a plurality of supporting insulators, a metal housing mounted on said insulators having a relatively thin circular resilient flange at its upper end, a tubular insulator of vitreous insulating material having a rigid fitting on its lower end secured at a plu-

rality of points to said resilient flange adjacent the edge of said resilient flange, stationary contact means and an arc extinguishing structure supported by said tubular insulator, and operating means for said movable contact disposed in said housing, said resilient flange permitting oscillation of said tubular insulator relative to said housing and preventing excessive stresses in said tubular insulator.
